UNITED STATES PATENT OFFICE.

JOHN E. RENFER, OF CLEVELAND, OHIO, ASSIGNOR TO THE CLEVELAND ROCK DRILL COMPANY, OF CLEVELAND, OHIO.

RETAINER FOR DRILL STEELS.

Application filed March 21, 1928. Serial No. 263,536.

The present invention is directed to improvements in retainers for collared drill steels used in connection with percussive drills.

5 The primary object of the invention is to provide a device of this character which can be easily and quickly attached to or removed from the front head of the drill, and is readily adjustable to retain the drill steel or 10 permit the release thereof.

Another object of the invention is to provide a retainer of this nature which is formed from a single length of suitable gage stock, the inherent resiliency thereof being 15 such that the shock incident to the drill steel collar striking the retainer will be effectively absorbed.

Another object of the invention is to provide novel cooperative means between the 20 front head of the drill and the retainer to hold the latter in its open or inoperative position, and in its operative position.

While the drawing illustrates a preferred embodiment of the invention it is to be understood that in adapting the means to meet specific needs and requirements the design may be varied and such other changes in the minor details of construction may be resorted to within the scope of the invention as claimed, 30 without departing from the spirit thereof.

For a full understanding of the invention and the merits thereof, reference is to be had to the following description and the drawing hereto attached, in which,—

35 Figure 1 is a side view.

Figure 2 is a top plan view, partly in section.

Corresponding and like parts are referred to in the following description and designated in the several views of the drawing by 40 like reference characters.

Referring to the drawing, 1 designates the front head of a drill of the percussive type, and upon opposite sides thereof are formed 45 recesses 2 and resultant semi-circular walls 3, the forward ends thereof terminating in abutments 4. It will be of course understood that the walls and abutments are integral parts of the front head.

50 These abutments have their inner faces provided with seats 5 and 6, and intermediate shoulders 7, the terminals thereof constituting stops 8, the purpose of which will be later ex-

plained. The retainer 9 is formed from suitable gage wire stock and is bent to provide 55 a yoke 10 to accommodate the drill steel 11, but of such size as to prevent the passage of the collar 12 therethrough when the retainer is in its closed or operative position.

The inner ends of the arms 13 of the retainer terminate in open coils 14 which are shaped to correspond to the contour of the walls 3. The terminals of the coils are formed to provide rounded lugs 15 for co-operation with the seats 5 and 6 and shoulders 60 7 in a manner to be hereinafter described. It will be obvious that when the coils 14 are confined by the walls 3 that a pivotal connection is formed between the front head and retainer in order that the retainer may conveniently 65 be swung to its open or closed position, as desired. The inherent resiliency of the coils serves to hold the retainer in either its open or closed position.

As shown in full lines in Figure 1 the lugs 75 15 are engaged in the seats 5 and owing to the resiliency of the coils, said lugs will be firmly maintained in said seats, thus holding the retainer in a position to locate the yoke 10 in advance of the collar 12 to arrest the outward 80 movement of the drill steel when rapidly driven forwardly by the hammer of the drill.

It will be obvious that the shock incident to the collar striking the yoke sharply will be absorbed by the coils 14, thus preventing 85 breakage and prolonging the life of the parts. When it is desired to remove the drill steel the retainer is swung to the position as shown in dotted lines in Figure 2, whereupon the coils will contract slightly and the lugs 90 15 will disengage the seat 5 and move into engagement with the shoulders 7, and at which time the side arms 13 will engage the stops 8. The yoke 10 will then be so positioned that the movement of the drill steel collar will not 95 be arrested thereby, thus permitting the drill steel to be removed.

To remove the retainer from the front head the side arms 13 are sprung apart a sufficient distance to clear the stops 8, and upon swinging the retainer laterally the side arms engage the bases of the seats 6, at which time the coils are fully disengaged from the walls 3. It is then only necessary to exert pressure 100 upon the retainer to disengage the same. To 105 replace the retainer the terminal lugs 15 are

placed in the seats 6 and the retainer swung until the coils are confined by the walls and the lugs again engage the seats 5.

Having thus described the invention, I claim:

1. The combination with the front head of a drill having a collared drill steel operable therein, of walls upon the opposite sides of the front head, said walls terminating at one of their ends in abutments, a drill steel retainer comprising a yoke and side arms, the inner ends of the side arms having coils for engaging the inner periphery of the walls, cooperative means carried by the terminals of the coils and abutments for holding the retainer with its yoke in a position to arrest the passage of the drill steel collar there-through or permit the passage thereof thereby.
2. The combination with the front head of a drill having a collared drill steel operatively associated therewith, of walls upon opposite sides of the front head, said walls terminating at one of their ends in abutments, said abutments having spaced seats therein, a drill steel retainer comprising a yoke and side arms, the inner ends of the side arms having coils thereon and having terminal lugs

for selective engagement with the seats to either hold the retainer with the yoke in a position to arrest the passage of the drill steel collar therethrough or to permit the passage thereof thereby.

3. The combination with the front head of a drill, of semi-circular walls upon the opposite sides thereof, one of the ends of the walls terminating in abutments having spaced seats therein, a drill steel retainer comprising side arms having their inner ends provided with open coils, said coils having intimate sliding engagement with the walls to permit pivotal movement of the retainer, lugs upon the terminals of the coils for selective engagement with the seats, as and for the purpose set forth.

4. The combination with the front head of a drill, of walls upon opposite sides thereof, of abutments carried by the walls, a drill steel retainer including side arms having resilient coils upon the terminals and pivotally confined by the walls, and means for interlocking the coils and abutments to hold the drill steel retainer in operative or inoperative position.

In testimony whereof I affix my signature.

JOHN E. RENFER.
